(57) **CLAIM**

The ornamental design for a multi-fold greeting card, as shown and described.

DESCRIPTION

FIG. 1 is a folded configuration view;

FIG. 2 is an open configuration view;

FIG. 3 is an open configuration view with partially unfolded insert;

FIG. 4 is an open configuration view with fully unfolded insert;

FIG. 5 is a top plan view; and,

FIG. 6 is a top side view.

The broken lines in FIGS. 1-4 and 6 are for the purpose of illustrating environmental structure and form no part of the claimed design.
